HIGH-VELOCITY TUYERE WITH VARIABLE SIZE COOLING MEDIUM PASSAGE

The present invention relates generally to an improvement in air blast nozzles and more particularly relates to such devices as tuyeres used in blast furnaces.

In blast furnace operations, circulating water cooling systems are employed in such devices as tuyeres in order that the heat transferred from the blast furnace to the tuyeres is carried away by the circulating water to minimize heat buildup in the tuyeres.

A number of prior art cooling systems are inefficient in heat removal for a number of reasons. In some instances, the cooling water passages generally at the nose end of the tuyere are so restricted in size in order to increase the water velocity at the nose end of the tuyere that a distinct danger of plugging of the cooling water passage is inherent with these devices. Other devices, while achieving the desired rate of flow for the cooling medium, are either too bulky in their construction or have a tuyere contour which requires special handling to properly install and position the tuyere within the furnace.

A significant improvement over these prior art tuyeres is disclosed in U.S. Pat. No. 3,351,335 which shows a tuyere which has a cooling system which increases the cooling efficiency of the tuyere by circulating the flow of water at a substantially higher velocity than had been utilized previously in other prior art devices. Additionally, the cooling rate of the convolute-shaped tuyere is sufficiently high that the molten iron will not burn the tuyere.

While the convolute-shaped cooling passage tuyere of the type shown in U.S. Pat. No. 3,351,335 has been a significant improvement over prior art tuyere devices, several disadvantages exist with this tuyere.

It is known that the nose end of the tuyere which projects further into the furnace is subjected to higher temperatures than the head end or remaining end of the tuyere. For example, the nose end of the tuyere may be exposed to temperatures in excess of 3,000° F. due to the heat radiated from the raceway which is located close to the nose end of the tuyere, and burning coke and rising furnace gases. The head end of the tuyere, which is located in the furnace wall is subjected to a much lower temperature in the range of about 2,300° F. as the gases near the wall of the furnace are lower in both velocity and temperature. Additionally, with high velocity tuyeres, skulling occurs wherein the slag in the furnace adheres to the back portion of the tuyere close to the head end. This adhesion of material to the outer wall surface of the tuyere provides an insulating effect to the back portion of the tuyere which serves to reduce the temperature to which the back portion of the tuyere is subjected. The overall effect of skulling however is to increase the temperature differential between the head end and nose end of the tuyere. It is contemplated that if the temperature of a tuyere installed in a blast furnace can be made more uniform throughout the tuyere, the life of the tuyere can be lengthened.

This is extremely important because a short tuyere life means that a blast furnace must be shut down to replace the tuyere once it becomes cracked or damaged. It can be appreciated that the shutting down of a blast furnace operation is very costly due to the time and labor required to replace damaged tuyeres as well as the loss of furnace output occasioned by the downtime of the furnace. It is known that the strain placed on the copper material from which the tuyere is generally made varies appreciably along the length of the tuyere due to the high temperature differential which exists between the head end and nose end of the tuyere. It is believed this metal strain of the copper causes the tuyere to develop cracks in the wall which leads to the destruction of an installed tuyere. Consequently, it is desired to reduce this temperature differential in the tuyere itself for the purpose of increasing tuyere life while at the same time providing a high velocity of the cooling medium throughout the tuyere, particularly at the nose end.

It has been found that if convolute-shaped passages are graduated in size progressing from the head end to the nose end of the tuyere, the temperature differential of the tuyere between the head and nose ends is significantly reduced even though a high temperature differential exists in the atmosphere to which the tuyere is exposed. The providing of a more uniform tuyere temperature along the length of the tuyere is achieved by utilizing a large cross-sectional area of the tuyere at the head end of the tuyere where the tuyere temperature is lowest and reducing the cross-sectional area of the convolute-shaped passage as it progresses toward the nose end of the tuyere where the tuyere temperature is the highest due to its location in a blast furnace.

This reduction in the large tuyere temperature differential or the procuring of a more uniform tuyere temperature throughout the tuyere length reduces the thermal strains and differential metal expansions which affect the tuyere causing the tuyere to crack.

Because the arrangement of the graduated cooling system of the tuyere of the present invention is in one cylindrical plane so that the tuyere shape is symmetrical about its centerline, the need for the inlet or outlet passage to cross over other cooling water passages thereby causing a hump in the tuyere or requiring a special tuyere contour is eliminated.

Further, in the new and improved tuyere of the present invention, a graduated convolute-shaped cooling passage provides the flow path for a cooling medium, e.g., water, traveling at a high velocity whereby the cooling medium travels in a substantially helical movement as it moves along the length of the tuyere and the tuyere temperature is substantially more uniform along the length of the tuyere.

The cooling medium which flows through the cooling medium passage in the tuyere of the present invention travels in a substantially helical movement as it moves along the length of the tuyere with the velocity of the cooling medium gradually increasing to its highest velocity at the nose end of the tuyere. It is expected that the ratio of the velocity at the nose end of the tuyere as compared to the velocity at the head end of the tuyere will be in the range of about 2 to 1 to 5 to 1 with the velocity at the nose end of the tuyere being in the range of about 10-20 f.p.s.

In the drawings:

FIG. 1 shows a fragmentary view of the tuyere of the present invention positioned within a wall of a furnace;

FIG. 2 shows a sectional view taken along line 2-2 of FIG. 4;

FIG. 3 shows a perspective view of the tapered cooling medium passage of the present invention;

FIG. 4 shows an end of the tuyere of the present invention; and

FIG. 5 shows a sectional view taken along line 5-5 in FIG. 2.

In the drawings and more particularly FIG. 2, there is shown tuyere 10 having head end 12 and nose end 11 which extends into the furnace. The tuyere has a central opening 13 throughout its length. Head end 12 is installed within furnace wall 6 and is located substantially outside the working lines of the furnace. Blowpipe 9, which blows hot air blasts into the furnace at a temperature in the range of about 1,500° F. to about 2,300° F. and at a rate of about 5,000-10,000 cubic feet per minute, engages with tuyere 10, the blowpipe fitting against recess 8, FIG. 2, of head end 12. Head end 12 is tapered to fit against a complementary tapered portion of tuyere cooler 7. The cooler serves to cool the head end of the tuyere which is not within the working lines of the furnace. Disposed between the inner wall 14 and outer tapered wall 15 is a cooling medium passage 17 through which a suitable cooling medium, e.g., water, is circulated for heat transfer purposes.

Passage 17, as more clearly shown in FIG. 3, is comprised of a first convolute-shaped section 18, a second inlet section 21, a third section 19 and a fourth outlet section 20. Convolute section 18 comprises a plurality of convolutions which, when bent into the cylindrical shape shown in FIG. 3, provide a cooling medium passage for substantially the entire length of tuyere 10. When the individual convolutes 22 are bent to form

the cylindrical shape, the edges 24, 25 of the convolutes, which normally would be in an abutting position if a complete cylinder were formed, are spaced apart for reasons to be described hereinafter.

As seen in FIG. 2, the cross-sectional area of the cooling medium passage in a direction substantially normal to the direction of flow of the cooling medium, is graduated in size from the head end of the tuyere to the nose end of the tuyere. Preferably, the cross-sectional area of the passage at head end 12 is substantially greater than the cross-sectional area of the passage at nose end 13. The reductions in the cooling medium passage progressing from the head end to nose end as shown in FIG. 2 vary inversely with the temperature to which the tuyere is subjected when installed in a blast furnace. In other words where the area of the cooling medium passage is smallest at the nose end of the tuyere, the temperature to which the tuyere is subjected is highest whereas, at the head end of the tuyere where the temperature to which the tuyere is subjected is lowest, the cross-sectional area of the cooling medium passage is the largest.

As seen in FIG. 1, the head end of the tuyere is outside of the working lines of the furnace and is in contact with the tuyere cooler 7. At that portion of the tuyere there is no severe heat imposed on the tuyere such that the portion 5 of the convolute-shaped passage is primarily a plenum chamber which can be made as large as desired to conserve water pressure and reduce metal weight.

Section 19 which has one end integral with convolute section 18 is a substantially tubular section whose remaining end terminates as an end of outlet section 20. Section 19 is tapered from the head end to the nose end. The remaining end of outlet section 20 is circular in shape and tapped to receive a threaded conduit means, not shown. Similarly, section 21 has one end which terminates into an end of convolute section 18 while the remaining end of inlet section 21 is circular in shape and tapped to receive a threaded water conduit, not shown, the inlet and outlet conduits serving to transport a cooling medium throughout passage 17. The cross-sectional area of sections 20, 21 at the point where these sections are to connect to inlet and outlet cooling medium conduits, are reduced in size as compared to the remaining cross-sectional area of these inlet and outlet sections.

Section 19 which extends for a major portion of the length of the cooling water passage is located in close proximity to edge 25 of convolute section 18 as seen in FIG. 3, while the remaining edge 24 of section 18 is spaced substantially away from section 19. If desired this space could be eliminated and edge 24 of convolute section 18 and section 19 could be located contiguous to each other. However, in some instances, it is desirable to have an additional injection conduit passage, not shown, in the tuyere and space has been provided for such occurrence.

While the tuyere cooling medium passage of the present invention has a variation in the size of the cooling medium passage as the passage progresses from head end 12 to nose end 11, the size of the nose end is designated to have a minimum velocity of about 5 f.p.s. with the velocity in most instances being in the range of 10—20 f.p.s. Moreover, the pressure drop between the head end and nose end of the tuyere design of the present invention with its graduated drop in cross-sectional area of the cooling medium passage, is less than the pressure drop in a convolute-shaped cooling medium passage which is uniform in cross-sectional area. As a result, the pump which is employed to pump water through a convolute-shaped tuyere having a uniform cross section area throughout the passage can be used to pump water through the tuyere cooling medium passage of the present invention without an increase in pressure and at the same time pass a higher flow rate of water through the graduated water passage. This increased flow rate is highly desirable in that the velocity of the cooling water at the nose end of the tuyere is increased significantly without having changed the cross-sectional area of the type disclosed in U.S. Pat. No. 3,351,335.

Whereas the flow rate for tuyeres presently employed is about 43—44 gallons per minute, the flow rate for the tuyere design of the present invention can be increased to about 50 gallons per minute. The cooling medium is directed through

5 cooling passage 17 where at the nose end, as seen in FIG. 2, the cross-sectional area of the passage is about 1.20 square inches whereas the cross-sectional area of the tuyere passage at the head end of the tuyere which is located within the working lines of the furnace is about 2.70 square inches. At the plenum chamber 5 the cross-sectional area is over 3.00 inches. The velocity can be designed to be approximately 5—20 f.p.s. at the nose end of the tuyere.

10 A specific embodiment of the tuyere has a length of 15 inches with a gas opening 13 of about 7 inches diameter, 15 although both of these dimensions can be varied.

15 The tuyere is preferably copper casting having the cooling water passage placed therein by means of a shell core. However, if desired, one could initially form a metal tubing to have a cooling medium passage comprising the convolute section, 20 substantially straight section and outlet and inlet sections after which the remaining portion of the tuyere could be cast around the formed tubing.

25 In addition to tapping inlet and outlet opening in the passage for receipt of conventional cooling water pipes, a third hole 30 is tapped into the tuyere. In removing the tuyere from its position in the blast furnace, a rod is screwed into tapped hole 30 and the tuyere can be pulled from the furnace wall.

30 Insulation 31 which lines opening 13 for a substantial portion of its length is employed to prevent heat loss from hot gas being blasted into the furnace, the insulation being generally $\frac{1}{2}$ -inch thick high aluminum costable refractory insulation or other suitable material.

35 The foregoing detailed description has been given for clearness of understanding only, and no unnecessary limitations should be understood therefrom as modifications will be obvious to those skilled in the art.

What we claim is:

- 40 1. A blast furnace tuyere which will be subjected to a high temperature differential along the length of said tuyere when the tuyere is installed in a blast furnace;
- 45 said tuyere comprising an outer wall, a nose end, a head end and an inner wall forming a central opening along the longitudinal axis of said tuyere;
- 50 a cooling medium passage disposed between said central opening and the outer surface of said tuyere, said cooling medium passage comprising:
- 55 a first convolute-shaped section curved about said longitudinal axis;
- 60 said convolute-shaped section having an inlet end and an outlet end and two edges;
- 65 said convolute-shaped section extending between said head end and said nose end of said tuyere and the cross-sectional area of said convolute section transverse to the direction of flow of a cooling medium, varying in size with the largest cross-sectional area of said tuyere being close to said head end of said tuyere and the smallest cross-sectional area being at the nose end of said tuyere;
- 70 said convolute-shaped section including means for progressively cooling from said head end toward said nose end of said tuyere;
- 75 one of said edges being spaced from said remaining edge; a second inlet section having one end integral with said inlet end of said convolute-shaped section, and another end terminating at said head end of said tuyere;
- 80 a third section having one end integral with said outlet end of said convolute-shaped section and extending from said nose end of said tuyere rearwardly toward said head end of said tuyere between said edges of said convolute-shaped section; and
- 85 a fourth outlet section having one end integral with the remaining end of said third section and another end terminating at said head end of said tuyere;
- 90 said cooling medium passage comprising said four sections;

whereby said cooling medium passage is adapted to receive a cooling medium which moves progressively from said head end toward said nose end and passes through said inlet section, said convolute-shaped section and said third section prior to exiting from said tuyere through said outlet section and the temperature of the tuyere when it is installed in a blast furnace being substantially uniform from said nose end to said head end. 5

2. A tuyere in accordance with claim 1 wherein said cross-sectional area of at least said convolute-shaped section decreases progressively said head end to said nose end of said tuyere. 10

3. A tuyere in accordance with claim 2 wherein said cross-sectional area from said head end to said nose end of the portion of the tuyere which is normally located within the working lines of said furnace decreases progressively and inversely proportional to the temperature to which said tuyere will be subjected along said outer wall when said tuyere is installed in a blast furnace. 15

4. A tuyere in accordance with claim 3 wherein said cross-sectional areas of at least said convolute-shaped portion increases in a ratio of about 1 to 2 to 1 to 5 from said nose end to that portion of said head end which is normally disposed within said furnace. 20

5. A tuyere in accordance with claim 4 wherein said cross-sectional area of said convolute-shaped section at said nose end is a minimum of about 1.20 square inches. 25

6. A tuyere in accordance with claim 4 wherein said third section has a rearward, outward taper from said nose end to said head end. 30

7. A blast furnace tuyere which will be subjected to a high temperature differential along the length of said tuyere when the tuyere is installed in a blast furnace; 35

said tuyere comprising an outer wall, a nose end, a head end and an inner wall forming a central opening along the longitudinal axis of said tuyere; a cooling medium passage disposed between said central opening and the outer surface of said tuyere, said cooling medium passage comprising: a first convolute-shaped section curved about said longitudi- 40

dinal axis; said convolute-shaped section having an inlet end and an outlet end and two edges; 5

said convolute-shaped section extending between said head end and said nose end of said tuyere and the cross-sectional area of said convolute section transverse to the direction of flow of a cooling medium, varying in size with the largest cross-sectional area of said tuyere being near said head end of said tuyere and the smallest cross-sectional area being at the nose end of said tuyere; said cross-sectional area from said head end to said nose end of the portion of the tuyere which is normally located within the working lines of said furnace decreases progressively and inversely proportional to the temperature to which said tuyere will be subjected along said outer wall when said tuyere is installed in a blast furnace; said convolute-shaped section including means for progressively cooling from said head end toward said nose end of said tuyere; 20

one of said edges being spaced from said remaining edge; a second inlet section having one end integral with said inlet end of said convolute-shaped section, and another end terminating at said head end of said tuyere; 25

a third section having one end integral with said outlet end of said convolute-shaped section and extending from said nose end of said tuyere rearwardly toward said head end of said tuyere between said edges of said convolute-shaped section; and, 30

a fourth outlet section having one end integral with the remaining end of said third section and another end terminating at said head end of said tuyere; 35

said cooling medium passage comprising said four sections; whereby said cooling medium passage is adapted to receive a cooling medium which moves progressively from said head end toward said nose end and passes through said inlet section, said convolute-shaped section and said third section prior to exiting from said tuyere through said outlet section and the temperature of the tuyere when it is installed in a blast furnace being substantially uniform from said nose end to said head end. 40
